ARTHUR E. LEHMANN, OF ST. CHARLES, MISSOURI, ASSIGNEE, BY MESNE ASSIGNMENTS, TO COMMONWEALTH STEEL COMPANY, A CORPORATION OF NEW JERSEY.

COMBINED BUFFER-BEAM AND END REINFORCEMENT FOR CARS.

1,124,040.

Specification of Letters Patent.

Patented Jan. 5, 1915.

Application filed December 15, 1913. Serial No. 806,804.

To all whom it may concern:

Be it known that I, ARTHUR E. LEHMANN, a citizen of the United States, residing at city of St. Charles, State of Missouri, have invented a certain new and useful Improvement in Combined Buffer-Beams and End Reinforcements for Cars, of which the following is a full, clear, and exact description, such as will enable others skilled in the art to which it appertains to make and use the same, reference being had to the accompanying drawings, forming part of this specification, in which—

Figure 1 is an elevational view of a combined buffer beam and end reinforcement of my improved construction, the same being shown applied to a blind end car. Fig. 2 is a horizontal section taken approximately on the line 2—2 of Fig. 1. Fig. 3 is a side elevational view of the combined buffer beam and car end reinforcement. Fig. 4 is a vertical section taken approximately on the line 4—4 of Fig. 1. Fig. 5 is an elevational view of the type of combined buffer beam or end sill and end reinforcement which is adapted for use in connection with box cars. Fig. 6 is a horizontal section taken approximately on the line 6—6 of Fig. 5. Fig. 7 is a side elevational view taken looking in the direction indicated by the arrow 7 in Fig. 6 and showing parts of the box car broken away. Fig. 8 is a plan view partly in section of a combined buffer beam or end sill and end reinforcement of the type adapted for use on the ends of gondola cars. Fig. 9 is an end elevational view of a portion of the form of buffer and end reinforcement seen in Fig. 8. Fig. 10 is a side elevational view of the end portion of a gondola car equipped with the form of buffer beam and reinforcement shown in Figs. 8 and 9. Fig. 11 is an end elevation of a portion of a gondola car having a combined buffer beam and reinforcement of my improved construction applied to the exterior thereof. Fig. 12 is a side elevational view of the end portion of a gondola car showing the same equipped with a combined buffer beam and outside reinforcement.

My invention relates generally to railway car construction, and more particularly to the construction of the ends of cars, the principal object of my invention being to provide an integral structure combining a buffer beam or end sill with a vertically

disposed frame, which structure materially reinforces the ends of cars and tends to eventually resist end shocks and crushing strains, thereby reducing to a minimum the tendency of car bodies to telescope during collisions.

In order to materially strengthen and reinforce the end portions of cars, various metal structures have been devised and are at present in general use, which structures include metal underframes, platforms, buffering sills, one piece end frames and reinforced corner posts, and to further strengthen and reinforce the ends of cars, I propose to provide a cast metal buffer beam or end sill and to form integral therewith one or more vertically disposed frames which will readily combine with the end wall construction to form a shock absorbing and resisting structure which materially reinforces and strengthens the extreme ends of the car superstructure.

My improved reinforcing structure can, with slight modifications, be advantageously combined with all forms of box cars, blind end cars and gondola cars.

With the above and other objects in view, my invention consists in certain novel features of construction and arrangement of parts hereinafter more fully described and claimed.

Referring by numerals to the accompanying drawings, and particularly to the construction illustrated in Figs. 1 to 4 inclusive, 1 designates a cast metal buffer beam which is preferably box shape in cross section throughout its length and provided at suitable points with internally arranged strengthening webs or flanges, and formed through the central portion of this buffer beam is a series of apertures 2 which are adapted to receive ordinary buffer stems.

Formed integral with and depending from the central portion of this buffer beam is a pair of lugs 3 which serve as supports for a suitable draw bar carry iron, and connecting the rear portions of these lugs is a longitudinally extending web 4. Formed integral with this web and extending rearwardly a suitable distance is one or more webs or flanges 4^a which serve as points of attachment for the center sill or sills of the car underframe. Formed integral with and projecting upwardly from the end portions of the buffer beam, are reinforcing mem-

- bers, preferably in the form of skeleton frames, each comprising an outer post or upright 5, an inner post or upright 6, and an intermediate post 7. Formed through the top plate of the buffer beam adjacent to the lower end of each inner post 6, is an opening 8 adapted to receive the lower end of the vestibule post 9 which in the present instance is shown as being formed of an I-beam.
- 10 Formed integral with the post or upright 6, and arranged on the front side thereof, is a wide vertically disposed flange 10 which bears directly against the web of the I-beam forming the vestibule post.
- 15 When the vestibule posts are applied to the buffer beam, the lower ends of said posts preferably rest on the bottom wall of said buffer beam, and said posts are rigidly attached to the posts 8 and flanges 10 in any suitable manner, preferably by means of rivets. The upper ends of each set of posts, 5, 6 and 7, are connected by a horizontally disposed rail 11, and formed integral with the ends 20 of the buffer beam and with the end posts 5, are rearwardly projecting vertically disposed plates or brackets 12 preferably provided with marginal flanges 12^a, and the lower ends of these plates bear upon and are 25 rigidly fixed to the end portions of the side sills 13 of the car underframe. Gusset plates 14 are formed integral with and arranged between the lower portions of the plates or brackets 12 and the end portions 30 of the buffer beam.
- 35 Formed integral with the buffer beam and projecting rearwardly therefrom, are webs or flanges 15 which serve as points of attachment for the ends of intermediate sills 16, which latter form a part of the car underframe. The lower portions of the corner posts 17 of the car body or superstructure are rigidly fixed in any suitable manner to the posts or uprights 5, and car end posts 18 40 of said superstructure are fixed to the intermediate posts or uprights 6.
- 45 Where a combined buffer beam and car end reinforcement of my improved construction is applied to cars which do not require end doors, the upper and lower portions of the posts or uprights 6 may be connected by transverse rails 19, as shown by dotted lines in Fig. 1. In this form of car end reinforcement, the buffer beam is rigidly fixed directly to the sills of the underframe and as the vertically disposed reinforcing frames are formed integral with said buffer beam, a very strong and rigid structure is produced which is anti-telescopic in effect for the reason that it tends to effectually resist all end shocks and crushing strains, such as may be developed during collisions.
- 50 The end reinforcement illustrated in Figs. 5, 6, and 7, is particularly designed for use in connection with box cars for either wood or metal superstructure. This construction includes a cast metal buffer beam 20 which is substantially box shape throughout its length, and formed integral with and depending from the central portion of said buffer beam are box shaped lugs 21 which serve as supports for the draw bar carry iron. Formed integral with the box shaped lugs and with the central portion of the buffer beam, are inwardly projecting webs or flanges 22 which serve as points of attachment for the center sills 23 of the car underframe.
- 55 Formed integral with and projecting upwardly from the end portions of the buffer beam, are posts or uprights 24, and formed integral with and projecting upwardly from the central portion of said buffer beam, are posts or uprights 25. The upper ends of the posts 24 and 25 are united by an integrally formed flanged rail 26. The posts 25 are preferably channel shape in cross section in order to receive the lower portions of the car end posts 27.
- 60 The lower portions of the corner posts 28 of the car body or superstructure combine with and are attached directly to the posts 24, and formed integral with these last mentioned posts and with the ends of the buffer beam 20, are rearwardly projecting vertically disposed plates or brackets 29, the lower ends of which rest upon and are 65 fixed directly to the ends of the side sills 30 of the underframe.
- 65 Formed integral with and projecting rearwardly from the buffer beam 20 are brackets 31 which are adapted to receive the intermediate sills 32 of the underframe, and arranged between the lower portions of the plates or brackets 29 and the end portions of the buffer beam, are integrally formed gusset plates 33. If desired, push pole pockets, such as 34, may be formed in the ends of the buffer beam. In this form of reinforcement, the one piece metal buffer beam is rigidly fixed to the ends of the sills of the underframe and the upright frame which is formed integral with said buffer beam provides a very strong, rigid and substantial reinforcement for the end portions of the car body, and which reinforcement not only resists end shocks and crushing strains, but prevents the end portions of the cars from spreading or bulging outwardly by reason of heavy loads.
- 70 The form of reinforcement illustrated in Figs. 8 to 10, inclusive, is particularly designed for use in connection with gondola cars, and the upright reinforcing frames in this form are arranged inside the sheathing or walls of the car. This structure includes a one piece cast metal buffer beam 35, preferably box or channel shape in cross section, and formed integral with and projecting up-

wardly from said buffer beam is a reinforcing frame comprising a series of uprights 36, the upper ends of which are united by a horizontally disposed flanged rail 37. Diagonally disposed braces 38 are formed integral with and arranged between the uprights 36 and between the buffer beam and top rail.

Formed integral with the ends of the buffer beam and the uprights which are located at said ends, are rearwardly projecting brackets 39, the lower ends of which are rigidly fixed to the side sills of the car underframe, and arranged between the lower portions of these brackets and the end portions of the buffer beam, are gusset plates 40. Where this form of reinforcement is used, the side and end sheets forming the walls of the car are applied directly to the outer faces of the upright frame and the plates or brackets 39, and said sheets are attached to these parts in any suitable manner, preferably by means of rivets.

In Figs. 11 and 12, the combined buffer beam and reinforcement is shown applied to the exterior of a gondola car and the vertically disposed reinforcing frame extends over one-half or two-thirds of the height of the body of the car.

If desired, the forms of reinforcing frames just described and shown in Figs. 8 to 12 inclusive may be combined with certain types of box cars, particularly those utilizing metal sheathing.

Combined buffer beams and end reinforcements of my improved construction are comparatively simple, can be cheaply produced, are adapted to be combined with various types of passenger, box and gondola cars, and when properly combined with the underframes and superstructures of said cars, provide a very strong and rigid structure which in case of collisions materially reduces the tendency of cars to telescope, thereby affording a maximum degree of safety to life and property.

It will be readily understood that minor changes in the size, form and construction of the various parts of my improved buffer beam and end reinforcement may be made and substituted for those herein shown and described, without departing from the spirit of my invention, the scope of which is set forth in the appended claims.

I claim:

1. A reinforcing structure for car ends comprising an integrally formed buffer beam, an upright car end reinforcing frame and carry iron supporting lugs.

2. A reinforcing structure for car ends comprising an integrally formed buffer

beam, an upright car end reinforcing frame thereon, carry iron attaching lugs on the underside of said beam, and side sill engaging brackets projecting from the ends of said buffer beam and upright frame.

3. A reinforcing structure for car ends comprising a buffer beam, a pair of upright frames integral with said buffer beam, side sill engaging brackets integral with the ends of said beam and the outer ends of said frames, and integral gusset plates between the end portions of the beam and the lower portions of the side sill engaging brackets.

4. A reinforcing structure for car ends comprising a buffer beam, side sill engaging gusset plates between the end portions of said beam and the lower portions of said brackets.

5. A reinforcing structure for car ends comprising a buffer beam, a series of uprights formed integral therewith, which uprights are adapted to engage the end wall structure of the car body, side sill engaging brackets integral with the ends of said buffer beam, and integral gusset plates between the end portions of said beam and the lower portions of said brackets.

6. A reinforcing structure for car ends comprising a buffer beam carry iron supporting brackets on the underside of said beam, a series of uprights formed integral therewith, which uprights are adapted to engage the end wall structure of the car body, and side sill engaging brackets integral with the ends of said buffer beam.

7. The combination with car underframe sills, of a buffer beam rigidly fixed to said sills, a vertically disposed reinforcing frame integral with said buffer beam, side sill engaging brackets integral with the ends of said buffer beam and integral gusset plates between the end portions of said beam and the lower portions of said brackets.

8. The combination with car underframe sills, of a buffer beam, extensions integral therewith for the attachment of said sills, car end reinforcing and strengthening members integral with and projecting upwardly from said buffer beam, side sill engaging brackets integral with the ends of said buffer beam and integral gusset plates between the end portions of said beam and the lower portions of said brackets.

In testimony whereof I hereunto affix my signature in the presence of two witnesses, this 5th day of December, 1913.

ARTHUR E. LEHMANN.
